UNITED STATES PATENT OFFICE.

ABRAHAM L. ABERCROMBIE AND JOHN P. CARTIN, OF DAYTONA, FLORIDA.

GARMENT-SUPPORTER.

1,064,416.

Specification of Letters Patent. Patented June 10, 1913.

Application filed August 3, 1912. Serial No. 713,117.

To all whom it may concern:

Be it known that we, ABRAHAM L. ABERCROMBIE and JOHN P. CARTIN, citizens of the United States, residing at Daytona, in 5 the county of Volusia and State of Florida, have invented certain new and useful Improvements in Garment-Supporters, of which the following is a specification, reference being had to the accompanying 10 drawings.

This invention comprehends certain new and useful improvements in garment supporters and relates particularly to supporters for trousers, the invention having for 15 its primary object an invisible belt, novel means for securing the belt to the trousers, and novel means for attaching suspenders to the belt, whereby suspenders may also be used in connection with the device with the 20 suspenders worn either inside or outside of the shirt.

The invention has for a further object a garment supporter of the character above indicated, which will enhance the neat appearance 25 of the wearer and which may be easily attached to or removed from the trousers.

Another and more specific object of the invention is an inside waist belt for the 30 trousers upon which a plurality of slides are arranged, said slides carrying a clamp, whereby the same may be conveniently attached to the trousers or means whereby they may be readily engaged with the ordinary 35 inside suspender buttons which are secured to the inner face of the waist band of the trousers, and also means for removably mounting a suspender attaching element upon the slides.

With these and other objects in view, as 40 will more fully appear as the description proceeds, the invention consists in the constructions, arrangements and combinations of the parts, that we shall hereinafter fully 45 describe and claim.

For a full understanding of the invention, reference is to be had to the following description and accompanying drawing, in which,

Figure 1 is a perspective view showing 50 our improved supporting device applied to trousers. Fig. 2 is an enlarged sectional view with parts in side elevation, the section being taken approximately on the line 2-2, 55 of Fig. 1. Fig. 3 is an enlarged elevation of one of the slides detached. Fig. 4 is a de-

tail perspective view of the suspender attaching element removed from the slide. Fig. 5 is a section similar to Fig. 2, illustrating another embodiment of the invention. 60 Fig. 6 is an elevation of the slide used in the modified form of the device, and, Fig. 7 is another embodiment of the invention illustrating a slightly different form of the clamp, whereby the slides are detachably 65 secured to the waist band of the trousers; this form of clamp being the well known patented Washburne clamp.

Corresponding and like parts are referred to in the following description and designated in the accompanying drawing by like reference characters.

Referring to the drawing, the letter T designates the upper portion of a pair of trousers, upon the inside of which a belt 5 is 75 arranged contiguous to the waist encircling edge of the trousers. This belt may be composed of any desired substance or material, either elastic or inelastic, as preferred, and is designed to carry any desired number of 80 slides 6 which may consist of any suitable substance or material possessing sufficiently stiff characteristics, either sheet metal, wire, or other suitable material. Each of these slides is formed with spaced longitudinal 85 slots 7, and an enlarged intermediate opening 8 between said slots. Through these slots and back of the opening 8, the belt 5 is intended to be passed. One end 9 of the 90 slide, said end being reduced in width in the present instance, although that is a matter of design, and it is to be understood our invention is not limited in this regard, is reversely bent upon itself, as indicated at 10. Upon the extremity of this reversely bent end of 95 the slide, a clamping member 11 is mounted, said clamping member within the purview of our invention being of any desired type or design, but in the embodiment of the invention now being described, being a pivoted angular clamping member, as best illustrated in Figs. 2 and 3. The hook or bend 10 of the slide 6 is adapted to be engaged over the upper edge of the trousers T so that the clamping element 11 is disposed upon 100 the outer side of the trousers. By swinging this element upwardly to the position shown in full lines in Fig. 2, one end thereof is forced into engagement with the trousers to bind upon the same and tightly clamp the 105 trousers against the end 9 of the slide. By swinging the outer end portion of the clamp- 110

ing member 11 downwardly and outwardly to the position indicated by dotted lines in Fig. 2, the slide may be released so that the said belt 5 may be removed from the 5 trousers.

The intermediate opening 8 of the slide 5 is preferably contracted at one end, as indicated at 12. This reduced end portion in the opening 8 is adapted to receive the 10 shank 14 of a suspender attaching member 15. This member in its preferred form, consists of a strip of metal, wire or other suitable material, reversely bent to provide a clamping portion 16. To one end of this 15 strip, the shank 14 is attached, said shank being provided with a head 14' which is adapted to engage upon one side of the slide when the shank is disposed in the contracted end portion 12 of the opening 8. The main 20 portion of the opening 8 is of a size to admit of the head 14' being passed therethrough so that the shank 14 may be engaged in the contracted end portion 12. The clamping portion 16 of the member 15 is designed to 25 be received through the button hole provided in the suspender tabs, one of which is illustrated at S in Fig. 2, and said clamping portion 16 by bearing against the tab, securely retains the suspenders in connection 30 with the attaching members 15.

It is to be understood that our invention is not limited to any form of clamping member or other means for engaging the slides on the waist belt, with the trousers, and that 35 the invention is not limited to the details of construction hereinbefore described, as various changes and modifications may be made in the construction, arrangement and proportions of the parts without departing 40 from the scope of the invention, as defined in the appended claim. For example, in Figs. 5 and 6 of the drawings, we have illustrated another embodiment of the invention, wherein the end 9' of the slide is provided 45 with a notch or recess 17 in its extremity having a contracted mouth or entrance portion. This recess in the slide is adapted to receive the shank of the usual button 15' which is ordinarily secured to the inner side 50 of the waist band of the trousers at the upper edge thereof. By the use of this form of the slides, the belt may be worn underneath the shirt, a portion of the shirt being carried into the recess 17 along with the 55 button 15'. The slide of this form of the invention is designated 6' and is formed with slots 7' and an intermediate opening 8' corresponding in construction and function to the slots 7' and opening 8' before 60 described.

As another embodiment of the invention, reference is to be had to Fig. 7 of the draw-

ing, where we have shown a clamp which is carried by the slide, whereby the belt 5 is retained in position upon the inner side of 65 the waist portion of the trousers. This is the well known Washburne form of clamp which is protected by patent, consisting of a spring plate 18 which is arranged within the hook 10 on the end of the slide. The 70 bill of the hook is provided with a longitudinal slot in which a pivoted clamping lever 11' is mounted. One end of this lever is adapted to bear against the end of the spring 18 to force the same into engagement 75 with the trousers and thus retain the slide in position thereon.

From the foregoing description in connection with the accompanying drawing, it is believed that the construction and manner 80 of use of our improved garment supporter will be clearly understood. The belt 5 may be easily and quickly attached to or detached from the trousers and is invisible when in use. It is worn just above the hips 85 where the body gives it a natural support, and yet it will support the trousers at the proper height, being designed to be made of different sizes for different lengths of trousers, as may please the wearer. The device 90 can be worn with comfort and does not impart a bulky appearance to the waist of the trousers, as is the case in the use of the ordinary belt. The slides may be formed of any suitable material or substance, either 95 sheet metal, wire, or other substance or material and may be readily formed or stamped out in the desired shape by means of a suitable die. Owing to the simplicity of the device, it will be obvious that the same can be 100 manufactured at comparatively small cost and it is manifest that the invention is of great convenience in practical use.

What we claim is:—

In a device of the character described, the 105 combination of a slide provided with spaced slots and further provided with an opening between the slots, said opening being of a greater width than the slots and arranged in parallel relation therewith, said slots being adapted to receive a belt which extends across the central opening, one end of said central opening being contracted and extending beyond the corresponding ends of the belt receiving slots and adapted to receive suspender attaching members. 110 115

In testimony whereof we hereunto affix our signature in the presence of two witnesses.
